UNITED STATES PATENT OFFICE

117,168

DESIGN FOR A TRANSPARENT SHOE COVER

Jacqueline Donovan, New York, N. Y.

Application August 16, 1939, Serial No. 86,729

Term of patent 7 years

To all whom it may concern:

Be it known that I, Jacqueline Donovan, a citizen of the United States and a resident of New York, in the county of New York, State of New York, have invented a new, original, and ornamental Design for a Transparent Shoe Cover, of which the following is a specification, reference being had to the accompanying drawing, forming a part thereof.

The figure is a perspective view of a transparent shoe cover showing my new design.

I claim:

The ornamental design for a transparent shoe cover, as shown.

JACQUELINE DONOVAN.
